UNITED STATES PATENT OFFICE.

JAMES F. FOSTER, OF BUFFALO, NEW YORK.

STOVEPIPE-ELBOW.

No. 853,580.

Specification of Letters Patent.

Patented May 14, 1907.

Application filed July 26, 1904. Serial No. 218,227.

To all whom it may concern:

Be it known that I, JAMES F. FOSTER, a citizen of the United States, residing at Buffalo, in the county of Erie and State of New York, have invented a new and useful Improvement in Stovepipe-Elbows, of which the following is a specification.

This invention relates to that class of pipe elbows, particularly stove pipe elbows, which are made of one piece of sheet metal and have crimps or corrugations in their middle or curved portion extending either partially or entirely around the elbow. Heretofore these elbows have been made with their straight end portions smooth or uncorrugated for the purpose of enabling the elbow to be readily fitted to the adjoining pipe. These smooth end portions unless the elbow is made of very heavy material, become easily dented and bent out of shape in handling and transportation so that when the elbow is put up for use, great difficulty is experienced in fitting the elbow snugly to the adjoining pipe and securing a smoke proof joint.

The object of my invention is to provide an elbow the end portions of which will retain their circumferential shape and possess strength and rigidity and at the same time the elbow by reason thereof can be produced from a much lighter and cheaper grade of material than is now used.

In the accompanying drawings: Figure 1 is a side elevation of a stove pipe elbow embodying my invention. Fig. 2 is an end view of the same. Fig. 3 is an enlarged longitudinal section of the lower portion thereof.

Like letters of reference refer to like parts in the several figures.

A is a stove pipe elbow of the class described having radial corrugations *a a* extending circumferentially from the throat to the outer side of the elbow. These corrugations are preferably pressed together at the inner or throat side of the elbow and take up the surplus metal produced by bending the pipe to form the elbow. Their number, arrangement and extent depend upon the nature of the bend to be given to the elbow and

may differ more or less in different elbows. 50 Between these corrugations and each end, the pipe is straight and has heretofore been left smooth and uncorrugated except in the upper end where sometimes short longitudinal crimps *b*, Fig. 2, are sometimes inserted to permit the elbow to be more easily fitted within the adjoining pipe. In these straight and uncorrugated end portions of the elbow are arranged a series of small beads or crimps *c c'* extending circumferentially 60 around the elbow. In that portion adapted to be fitted over the adjoining pipe, generally the lower portion, these beads project outwardly as shown at *c*, Figs. 1 and 3, so as to form no obstruction on the inner side of the 65 elbow, while in that portion adapted to be fitted within the adjoining pipe, generally the upper portion, the bead projects inwardly as shown at *c'*, Fig. 1, so as to form no obstruction on the outer side of the elbow. By this 70 arrangement, the beads do not project on that side of the elbow which comes in contact with the adjoining pipe and therefore permit a close fitting joint between the two to be made. These beads may be formed in 75 the metal at any desirable time during the process of manufacturing the elbow, either when the metal is in the blank, or after the pipe is formed, or after the elbow is made, and any suitable beading machine may be 80 employed for such purpose. It is desirable to place one of these beads as near each end of the elbow as possible and when the end is crimped longitudinally the bead is placed adjacent to these crimps. These beads give 85 strength and rigidity to the end portions of the elbow and hold the same in shape. They thus permit the adjoining pipe to be easily fitted thereto and a close fitting joint secured. The number of beads employed is 90 determined by the character of the metal used, a lighter grade of metal requiring a greater number of beads to give the elbow the necessary strength and rigidity. At the end of the elbow which is provided with longitudinal crimps *b* a single circumferential bead *c'* is usually sufficient. It is obvious 95 that this improvement is not limited to the

particular form of elbow shown in the drawings but can be applied to any elbow having a smooth uncorrugated end portion.

I claim as my invention:—

5 A sheet metal elbow having a curved body portion and straight end portions, said end portions having beads formed therein which extend around the same and are of uniform size throughout the circumference thereof,

10 said beads projecting inwardly in one of said end portions and outwardly in the other, substantially as set forth.

Witness my hand this 20th day of July, 1904.

JAMES F. FOSTER.
